CLAIM

The ornamental design for a light fixture, as shown and described.

DESCRIPTION

FIG. 1 is a bottom perspective view of a light fixture showing our new design;

FIG. 1A is an alternate bottom perspective view thereof;

FIG. 2 is a top perspective view thereof;

FIG. 3 is a bottom view thereof;

FIG. 4 is a top view thereof;

FIG. 5 is a front view thereof, wherein the rear view, right side view and left side view are mirror images and identical thereto; and,

FIG. 6 is a cross-sectional view at 6-6 in FIG. 2 thereof. The broken lines immediately adjacent to the shaded areas represent unclaimed boundaries of the design, and the remaining broken lines represent portions of the fixture which form no part of the claimed design.
